PETROLEUM REFINING

Wallace A. Craig and Paul C. Rich, Los Angeles,
Calif., assignors to Richfield Oil Corporation,
Los Angeles, Calif., a corporation of Delaware

Application February 17, 1940, Serial No. 319,437

5 Claims. (Cl. 196—41)

This invention is concerned with the prevention of corrosion of vessels employed in handling petroleum products in oil refineries and the like, and contemplates the treatment of certain types of petroleum products, such as sour gasoline, to extract therefrom aliphatic acids containing not to exceed six carbon atoms per molecule, for example, formic, acetic, and propionic acids and the butyric and the valeric acids. Such acids tend to form through side reactions which occur during the cracking of petroleum from some fields and exert a powerful corrosive action on iron and steel containers and conduits and also exert a deleterious effect in certain present day petroleum refining processes.

We have discovered that raw gasoline and other relatively low-boiling petroleum products formed by cracking some petroleums, for example, certain Los Angeles Basin Crude Oils, exert a powerful corrosive influence upon iron and other metals with which they come in contact. The corrosive tendency of these products is due to a relatively small but exceedingly active proportion of aliphatic acids having not more than six carbon atoms per molecule and exemplified by formic, acetic and propionic acids and the butyric and the valeric acids. These acids are formed in the petroleum products during cracking and are miscible with and are dissolved in the lower-boiling products of the cracking (such as gasoline) at the concentration at which these acids are produced. In large part, the acids distill with that fraction of the products that boils below about 200° F. and become concentrated in this fraction. It is with this fraction that corrosion difficulties are serious. The acids, in the presence of a small proportion of water almost inevitably contained in the fraction, exert a strong corrosive influence. Moreover, the acids contained in this fraction cause difficulty in subsequent refining steps. Thus, these acids may bring about serious corrosion at all points in a modern petroleum refinery from the bubble tower in the cracking section from which crude gasoline is derived through the various refining steps until they are either removed from the system or are neutralized in some specific operation. We have, for example, experienced degradation of tri-potassium phosphate solution, used for removing the hydrogen sulfide from the gaseous charge to the polymerization unit, due to the reaction of the tri-potassium phosphate with the organic acids. This is objectionable and can be avoided by the practice of our invention.

As a result of our investigations, we have discovered that the corrosive action of sour gasolines and other low-boiling mixtures of hydrocarbons containing some water plus aliphatic acids of six or less carbon atoms per molecule is substantially reduced by washing the gasoline or the like with water or other aqueous body. Water alone serves to extract the acids, particularly those having fewer carbon atoms per molecule. Thus, by washing with water or equivalent non-alkaline aqueous fluid, substantially all of the formic and acetic acids can be extracted from raw gasoline. The water also tends to extract the higher acids but less thoroughly, i. e., there is a decrease in the efficiency of extraction of propionic acid, the butyric acids and the valeric acids in the order named. These heavier acids, however, may be extracted with substantial completeness by subsequently washing the gasoline or other product with an aqueous alkaline solution, but from the standpoint of corrosion reduction, such additional washing is seldom necessary, for the higher acids appear to be more sluggish in their corrosive action. The acid content extractable by water alone is that which otherwise would bring about intolerable corrosion.

In accordance with our invention, the water washing should be conducted, in a petroleum refinery where the acids occur, as early as possible after preliminary fractionation has concentrated the aliphatic acids in the low-boiling fraction of hydrocarbons. In other words, maximum advantage in the use of our invention is gained through extracting the acids as soon as possible after they have been formed and have had an opportunity to associate with water and gain an objectionable concentration. Thus, we have found that raw gasoline and lighter hydrocarbons formed directly through cracking (or by the alkylation or polymerization of lower hydrocarbons, including some that have resulted from cracking) should be treated as early in the process as possible in order to extract the acids.

Single stage washing with water at atmospheric temperatures will in most cases extract the larger proportion of the more corrosive acids and may suffice when prevention of corrosion is the principal end of the operation. However, multi-stage washing, preferably in countercurrent series, accomplishes a more thorough removal of the acid and is desirable when the acids are recovered for use or when single stage washing does not sufficiently inhibit corrosion.

Almost any type of scrubbing equipment that will assure adequate contact of water and the petroleum product being treated may be used. Thus, the water may be permitted to percolate downward through a large tank of raw gasoline. However, it is preferable to employ agitators or other apparatus to assure adequate mixing of the gasoline and the water, followed by a settler of conventional type from which the washed gasoline is decanted. Washing of the gasoline or other hydrocarbon product in the vapor phase may be accomplished in a tower or the like in which the vapors pass countercurrent to the water.

We have found that more efficient washing (from the standpoint of water consumed) and a stronger aqueous solution of the acids may be obtained by circulation of the wash water, and that a substantial concentration of the acids in the water may be built up through such circulation without serious effect upon the degree of extraction. The dilute acid solution which is separated from the gasoline may be treated to obtain a more concentrated form of the acid or to separate the various acids from each other. This may be accomplished by fractional distillation.

Whether or not a product of petroleum cracking will contain initially the aliphatic acids with which we are concerned depends, we believe, principally upon the nature of the petroleum, which, in turn, is dependent upon the field from which it is produced. Thus, crude oil from the Wilmington (California) field is converted by cracking into products containing substantial proportions of these acids. The same is true with respect to crudes from other fields in the Los Angeles basin. On the other hand, crudes from fields in certain other sections of the country do not yield products containing appreciable quantities of these acids even though subjected to cracking and subsequent treatment in identical apparatus. In no instance, so far as we are aware, is there a large proportion of such acids in the petroleum product, and it might well be supposed that the small amount present would have no harmful effect. The fact is, however, that in the presence of the water which almost inevitably occurs in at least a small proportion in the products of pyrolytic cracking, the acids exert a profound corrosive influence. Thus, a sour gasoline containing 0.01 mol per liter of aliphatic acids brings about serious corrosion of refinery equipment.

To take a typical example, the total acid content (0.01 mol per liter of distillate) of a sour gasoline may be divided as follows:

Table I

Acid ingredients	Portion of total acidity	Approximate content per 1000 bbl. of gasoline
	Per cent	Pounds
Formic acid	55	44.25
Acetic acid		57.75
Propionic acid	18	23.25
Butyric acids	27	27.70
Valeric acids and heavier		96.25
	100	

It will be observed that even with such a small proportion of total acid in the gasoline, the total weight of the acids in the total gasoline produc-

tion of a large refinery is substantial. In fact, gross value of the acids extractable by water washing from a gasoline of the above type is, based upon recent market quotations, approximately \$11.25 per 1000 bbl. of gasoline produced.

The efficiency of extraction of the lighter and heavier acids by water washing of various types is given in the following table:

10

Table II

Type of wash used	Percent of original acid remaining in gasoline		
	Acetic acid	Propionic acid	Iso-butyric acid
1 stage:			
5% wash water	10	64	92
10% wash water	5	44	84
20% wash water	3	26	71
20			
2 countercurrent stages:			
5% wash water	2	50	91
10% wash water	1	25	82
20% wash water	1	8	65
3			
3 countercurrent stages:			
5% wash water	1	46	90
10% wash water	1	17	81
20% wash water	1	3	64
25			

In the foregoing table and hereinafter the percentages of wash water are calculated on the volume of the gasoline washed.

The various washing procedures, the results of which are tabulated above, employed water at approximately atmospheric temperature and an effort was made to mix gasoline and water thoroughly in each stage, mixing being followed by settling and decantation of the gasoline. It will be observed that acetic acid is extracted relatively thoroughly in a single washing stage with as little as five per cent (5%) wash water on the volume of the gasoline, and that extraction of acetic acid is not improved substantially by employing more than 2 countercurrent washing stages with ten per cent (10%) wash water in each stage. Formic acid is, like acetic acid, thoroughly extracted with but a slight water treatment. Propionic acid, on the other hand, can be extracted thoroughly by water washing but requires a prolonged treatment. Thus, single stage washing with five per cent (5%) wash water leaves 64 per cent of the propionic acid in the gasoline and an extraction of 97 per cent of the propionic acid is not obtained until it has been washed in 3 countercurrent stages with twenty per cent (20%) by volume of wash water.

Washing treatment that will extract substantially all of the acetic and formic acids and a reasonably large proportion of the propionic acid will leave most of the butyric acids and heavier acids in the gasoline. Thus, 3 stage countercurrent washing employing twenty per cent (20%) of wash water will extract in excess of 99 per cent of the acetic acid and 97 per cent of the propionic acid but will leave 64 per cent of the iso-butyric acid unextracted. Less thorough washing procedure will leave an even larger percentage of iso-butyric acid in the gasoline, and it is possible to conserve 91 per cent of the iso-butyric acid while extracting 98 per cent of the acetic acid, and 50 per cent of the propionic acid, this being accomplished in 2 countercurrent washing stages employing five per cent (5%) by volume of wash water.

The overall extraction efficiency of the various acids from the distillate by the various wash-

ing procedures described may be indicated as follows:

Table III

	Per cent of original acids remaining in product after washing
1 stage:	
5% wash water	46.6
10% wash water	41.3
20% wash water	37.4
2 countercurrent stages:	
5% wash water	40.8
10% wash water	37.1
20% wash water	34.1
3 countercurrent stages:	
5% wash water	39.8
10% wash water	36.3
20% wash water	33.5

The relatively poor attraction by water alone of the acids of higher molecular weight accounts for the relatively large percentage of the original aliphatic acid content of the gasoline or other hydrocarbon that remains after washing. However, from the standpoint of corrosion, it is unnecessary to carry out water washing to extract more than say about 60 per cent of the total acids. Thus, employing 2 stage countercurrent washing, applying five per cent (5%) wash water on the volume of the product being washed, the following results are obtained in washing a cracked distillate containing .01 mol total aliphatic acids per liter. On this basis, a wash water of the following analysis is formed:

Table IV

Acids in the water wash (basis 50 bbl. water/1000 bbl. of gasoline)

	Lb./bbl. of water
Formic acid	0.0539N 13.9
Acetic acid	0.0539 18.1
Propionic acid	0.0090 3.7
Butyric acids	0.0016 0.8
Valeric acids and heavier	0.0000 0
	0.1184N 36.5

The total residual acid in the washed cracked distillate following the 2 stage washing outlined above has the following acid content:

Table V

Residual acid in the washed cracked distillate= 0.00408N containing

	Lb./1000 bbl. of oil
Formic acid	0.000055N 0.875
Acetic acid	0.000055 1.125
Propionic acid	0.00045 11.625
Butyric acids	0.00082 25.250
Valeric acids and heavier	0.00270 96.250
	0.00408N 135.125

Since corrosion is principally due to the acids of lower molecular weight, say formic acid and acetic acid, extraction of these acids alone while leaving the heavier acids in the distillate for subsequent extraction by alkali washing is desirable. We have discovered that a large proportion of the formic acid and the acetic acid, and a smaller proportion of the propionic acid tends to distill with a very light fraction of the cracked hydrocarbons driven off during stabilization treatment, for example, the overhead product of a deutanizer comprising butane, isobutane, and lighter hydrocarbons that are normally gaseous. Thus, 75

corrosion difficulties following the deutanizer can be completely eliminated by subjecting only the overhead of the deutanizer to water washing. This washing can be conducted either with the hydrocarbons in liquid phase or vapor phase. Since the deutanizer overhead is normally gaseous, it may be advisable to wash it in vapor phase, employing a scrubbing tower through which the vapors pass in countercurrent to a water wash.

If the lighter acids are extracted from the deutanizer overhead or other light fraction, the other and heavier acids which have commercial value but which do not bring about excessive corrosion, may be extracted from the heavier fraction or from merged gasoline products following polymerization or the like. The extraction by washing with alkali of propionic and butyric acids is described in detail in our pending application Serial No. 319,436, filed February 17, 1940, and is shown diagrammatically on the accompanying flow sheet which also illustrates the preliminary water washing described above for the selective removal of formic and acetic acids.

We claim:

1. In the treatment of a petroleum hydrocarbon product containing formic acid, acetic acid and a butyric acid, said treatment involving contact of the hydrocarbon product with metal, the improvement which comprises washing the product with water until a relatively large proportion of the formic acid and the acetic acid are extracted while a relatively large proportion of the butyric acid is left in the product, thereby reducing the corrosive action of the product upon the metal in the presence of water.

2. In the treatment of a petroleum hydrocarbon product containing formic acid, acetic acid and a butyric acid, the improvement which comprises subjecting the product to fractional distillation to vaporize and separate a fraction containing low-boiling hydrocarbons and the formic and acetic acids while leaving a large proportion of the butyric acid in the residual liquid and subjecting the fraction thus separated to water washing to extract the formic and acetic acids therefrom, whereby the corrosive action of the fraction and of the residual liquid upon metals in the presence of water is reduced.

3. In the treatment of a petroleum hydrocarbon product containing a relatively small proportion of water and formic acid, acetic acid, propionic acid and a butyric acid, which treatment involves contact of the hydrocarbon product with metallic containers, the improvement which comprises washing the product with a relatively large volume of water until a substantial proportion of the formic acid, acetic acid and propionic acid has been extracted from the product while leaving a large part of the butyric acid therein, and thereafter separating the wash water from the hydrocarbon product thereby reducing the corrosive activity of the latter.

4. In the treatment of a petroleum hydrocarbon product containing formic acid, acetic acid, propionic acid and a butyric acid, the improvement which comprises subjecting the hydrocarbon product to water washing until a large proportion of the formic acid and the acetic acid and a smaller proportion of the propionic acid has been extracted, the butyric acid in large part being left in the hydrocarbon product, separating the wash water containing the formic acid, acetic acid and propionic acid from the hydro-

carbon product, and treating the hydrocarbon product thus separated with an alkaline aqueous solution to extract the butyric acid therefrom.

5. In the treatment of a petroleum hydrocarbon product containing formic acid and propionic acid and at least one of the butyric acids, the improvement which comprises washing the product with water until a large proportion of the formic and acetic acids and a smaller pro-

portion of the propionic acids have been extracted, separating the resulting water solution of these acids from the treated product, thereafter extracting the butyric acid from the treated product by washing it with an aqueous alkaline solution, and separating the aqueous alkaline solution from the product.
